RACK FOR DENTAL HYGIENE APPLIANCES OR THE LIKE

Frederick Gordon Mackay and Allan B. Johnson, Tarzana, Calif., and John W. Mattingly, Fort Collins, Colo., assignors to Aqua-Tec Corporation, Fort Collins, Colo., a corporation of Colorado

Filed Sept. 9, 1966, Ser. No. 3,785

Term of patent 14 years

(Cl. D24—1)

FIG. 1

FIG. 4

FIG. 2

FIG. 5

FIG. 3

FIG. 6

FIG. 1 is a perspective view of a rack for dental hygiene appliances or the like, showing our new design; FIG. 2 is a side elevation thereof;

FIG. 3 is a top plan view thereof;

FIG. 4 is a front elevation thereof;

FIG. 5 is a bottom plan view thereof; and

FIG. 6 is a cross section taken along line 6—6 of FIG. 3.

We claim:

The ornamental design for a rack for dental hygiene appliances or the like, as shown.
